Primary Examiner — Robin V Webster*Assistant Examiner* — J. Thorn, Sr.(74) *Attorney, Agent, or Firm* — Ferguson Case Orr Paterson LLP(57) **CLAIM**

The ornamental design for a PPR bra, as shown and described.

DESCRIPTION

FIG. 1 is a front perspective view of a PPR bra in accordance with the new design;

FIG. 2 is a rear perspective view thereof;

FIG. 3 is a front view thereof; and,

FIG. 4 is a rear view thereof.

The broken lines shown in the drawings represent stitching in the fabric.
